PAPER SHEET DISPENSING BOX

Nathan Fleischer, Brooklyn, N. Y.

Application November 28, 1939, Serial No. 306,433.

5 Claims. (Cl. 206—57)

This invention relates to a paper sheet dispensing box and is an improvement over the paper dispensing pack set forth in my Letters Patent No. 2,207,917, issued July 16, 1940.

The primary object of the invention is to provide a cardboard box in which typewriter paper, office letter heads, and the like may be packaged for use and which may be kept in the desk drawer of a typist for convenient use as the paper stock is needed, thus eliminating the usual practice of loosely placing a supply of sheets in the desk drawer which exposes them to soiling by dust, and to damage by the corners accidentally becoming creased.

Another feature of the invention resides in a folding box formed from a single blank of cardboard which completely seals a supply of paper sheets therein to protect the sheets against exposure to handling and which is provided with a novel tear-away portion which facilitates individual access to the packaged sheets for convenient withdrawal as and when needed by the user thereof.

A further feature of the invention is the provision of a folding paper box of the kind above set forth, which is simple and inexpensive of construction, which may be stored in a flat unfolded position for shipment and storage purposes to conserve storage space, and which may be expeditiously set up for use; and which will enable a manufacturer of a trade-marked brand of paper sheets to attractively package and display the packaged goods in stack form upon the shelves of a retail store.

Other features of the invention will appear as the following specification is read in conjunction with the accompanying drawings, in which:

Figure 1 is an inside plan view of the blank from which the paper dispensing box is constructed.

Figure 2 is a fragmentary plan view of the front end of the blank showing the front wall folded and secured to the bottom wall.

Figure 3 is a perspective view of the box in folded set up position.

Figure 4 is a fragmentary bottom plan view of the rear portion of the folded box.

Figure 5 is an enlarged fragmentary vertical transverse sectional view on the line 5—5 of Figure 3.

Figure 6 is a vertical transverse sectional view on the line 6—6 of Figure 3.

Figure 7 is a vertical transverse sectional view on the line 7—7 of Figure 3.

Figure 8 is an enlarged vertical longitudinal sectional view on the line 8—8 of Figure 3.

Figure 9 is an enlarged vertical longitudinal sectional view through the front end of the box showing the tear away portion removed and the manner in which a paper sheet is removed by the fingers of a user.

Figure 10 is a fragmentary top plan view of a blank illustrating a modified form of the invention.

Figure 11 is a fragmentary top plan view of the modified form of blank in set up position.

Figure 12 is an enlarged vertical transverse sectional view on the line 12—12 of Figure 11.

Referring to the drawings by reference characters, and at present to Figure 1, the letter A designates a blank of foldable cardboard from which my paper sheet dispensing box is constructed and which is substantially rectangular configuration in plan and cut and scored in a manner now to be described. Before describing the scoring of the blank A, it is to be understood that the right side of the blank in Figure 1 constitutes the front end of the box to be constructed and the left side represents the rear end of the box.

A bottom wall 10 is formed from the lower portion of the blank A and is bounded by the rear edge 11 of the blank, longitudinal score lines 12 and 13, and a transverse score line 14. The score line 13 is disposed parallel to the bottom edge of the blank and the stock material therebetween constitutes a side wall 15, the front end of which terminates in a rearwardly inclined edge 16, the inner end of the edge 16 meeting one end of the score line 14. Integral with the side wall 15 at the rear end thereof is a corner flap 17, the same being separated from the side wall 15 by a rearwardly inclined score line 18 which is parallel to the front inclined edge 16. Divided from the bottom wall 10 by the score line 14 is a front wall 19 which is divided by a transverse score line 20 into an outer front wall section 21 and an inner front wall section 22, the latter having a score line 23 extending transversely thereof adjacent the free front edge to provide a glue flap 24. Parallel score lines 25—25 extend at right angle to the score lines 14 and 20 from the score line 14 to the front edge of the front wall section 22 for the purpose of reinforcing the front wall when the blank is folded to box forming position. Integral with the opposite end of the inner front wall section 21 are triangular shaped side flaps 26—26 which are foldable at right angles to the front wall.

section 21 on the score lines 27-27 which are continuations of the score lines 12 and 13 respectively. Each triangular shaped side flap 26 is provided with a female snap fastener element 28, the open sockets of the female snap fastener element 28 being disposed on the inner side of the blank and the heads thereof on the outer side for a purpose to be presently explained.

A rectangular shaped top wall 29 is formed from the upper portion of the blank A and is bounded by a longitudinal score line 30 which is parallel to the score line 12 and spaced a distance corresponding to the width of the side wall 15 to provide a side wall 31 intermediate the bottom wall 10 and the top wall 29. The top wall 29 is further bounded by a rear transverse score line 32, a front transverse score line 33 and a longitudinal score line 34, the latter separating the top wall 29 from an attaching flap 35. The score lines 32 and 33 are forwardly offset with respect to the rear edge 11 and the front score line 14 of the bottom wall 10 for a purpose hereinafter appreciated.

The side wall 31 is provided with a forwardly inclined front edge 36 and the rear end of the side wall 31 has a rear corner flap 37 integral therewith and which is inwardly foldable on the forwardly inclined score line 38 which extends from the edge 11 to the score line 32.

The transverse score line 33 separates the top wall 29 from the separable front end flap 39. The top wall 29 adjacent the front end thereof has a pull tab 40 cut therefrom and the ends of the slits forming the pull tab are joined by weakened tear lines 41-41 which join the weakened lines 42-42 in transverse alignment with the fold line 33.

Integral with the rear end of the top wall 29 and separated therefrom by the score line 32 is a rear end wall or closure 43 which is separated by a transverse score line 44 from an inwardly foldable end flap 45, the said flap having a score line 46 extending transversely thereof but merely for reinforcing purposes. The rear end flap 46 is provided with a slot 47 closely adjacent the score line 44 to receive a centrally located locking tongue 48 formed integral with the bottom wall 10 and hinged along the score line 49, the flap 48 having a transverse score line 50 which enables the tongue to be bent and inserted into the slot 47 when the box is in erected position.

Mounted in the side wall 31 adjacent the front end thereof is a male snap fastener element 51, the head end of which is disposed on the outer side of the side wall. The side wall 15 is similarly provided with a male snap fastener element 51, but this particular element is not applied until the attaching flap 35 is glued to the inner side of the side wall 15, thus the snap fastener element 51 associated with the side wall 15 passes through the side wall 15 and the attaching flap 35.

The initial step in the folding of the blank A is illustrated in Figure 2 of the drawings and consists in folding the front wall 19 on the score line 20 so that the glue flap 24 overlies the inner side of the bottom wall 10 and is attached thereto by the adhesive applied by reason of the flap 24. The next operation is to fold the blank on the longitudinal score line 30, thus bringing the attaching flap 35 in a position over the bottom wall 10 where it will be overlapped by the glue surface on the side wall 15. The box is now partially folded and is in a flat condition for compact stacking and shipping, but when it is de-

sired to complete the setting up of the box for the reception of a paper pack, an operator applies inward pressure along the folds formed by the score lines 30 and 13, thus causing the top and bottom walls 29 and 10 to be moved into separated spaced relation with the side walls 15 and 31 in a vertical upright position. The front wall of the box may now be closed by first folding the front end flap 39 downwardly on the fold line 33 and weakened lines 42-42, after which the folded front wall 19 is swung upwardly on the score line 14 until it abuts the inclined front edges 16 and 36 of the side walls 15 and 31 respectively, whereupon the triangular end flaps 26-26 are swung inwardly on the score lines 27-27 and the female snap fastener elements 28-28 are engaged with the male snap fastener elements 51-51. The front end of the box having now been closed, the paper pack consisting of a stack of sheets as shown in Figure 9 and designated S, are inserted through the rear open end of the box and when the paper pack is fully inserted, the front ends of the sheets engage the front end flap 39 which flap is disposed at an angle substantially parallel to the angle of the front wall. The rear end of the box may now be closed by first folding the rear corner flaps 17 and 37 inwardly on the respective fold lines 18 and 39, after which the rear end wall 43 is folded on the score line 32 and the flap 45 is folded on the score line 44 and inserted inwardly so as to lie against the bottom wall 10. To lock the rear end wall 43, the tongue 48 is folded inwardly on the line 50 and the free end inserted into the slot 47. The paper sheet dispensing box is now in completely folded set up position and it is assumed that it is desired to open the box to facilitate the individual dispensing of the paper sheets S. To open the box, the operator grasps the pull tab 40 and pulls outwardly thereon to tear away the front portion of the top wall 29 to provide a finger receiving opening 52 and continues to pull in order to completely tear away the front end flap 39 along the tear lines 42-42. After the front end flap 39 has been completely freed from its connection with the top wall 29, the same is withdrawn from the box and thrown away, and the tearing away of this flap provides a narrow slot 53 which extends transversely of the box at the front top edge. By reference to Figure 9 of the drawings, it will be seen that a person desiring a sheet of paper from the box may insert the forefinger through the opening 52 and slide a sheet of paper outwardly through the slot 53. By reason of the angularity of the front and rear walls of the box, the front edges of the paper sheets are held disposed in a position to be reached by the fingers of an operator when inserting the same through the openings 52.

In Figures 10 to 12 inclusive, I have shown a slight modified form of the invention wherein the use of the snap fastener elements for securing the front wall in erected position is dispensed with, and in lieu thereof, each triangular shaped flap 26 has an inwardly foldable locking tongue 54 integral therewith and which tongues are foldable relative to the flaps 26 on the fold lines 55. The tongues 54-54 are foldable over the top wall 29 and are insertible into pairs of locking slots 56-56. Also in this form of the invention, I dispense with the gluing of the flap 24 to the bottom wall 10, and in lieu thereof the bottom wall 10 has locking tabs 57 struck inwardly therefrom and beneath which the flap 24 of the front end wall section 22 engages.

From the foregoing description, it will be appreciated that I have provided a simple and inexpensive cardboard box in which sheets of type-writing paper and the like may be packaged and dispensed in a clean and fresh condition as the occasion requires. The top wall 29 of the box may contain the trade-mark of the manufacturer of the paper sheets, and any other printed indicia which may be necessary for instructing the user in the opening of the box. Also, due to the inclined front wall of the box, the trade-mark, grade of paper, and the like may be printed thereon and be clearly visible to view when boxes containing the paper sheets are stacked one upon the other upon shelves of a retailer.

While I have shown and described what I consider to be the most practical embodiment of my invention, I wish it to be understood that such changes and alterations as come within the scope of the appended claims may be resorted to if desired.

Having thus described the invention, what I claim as new and desire to secure by Letters Patent of the United States is:

1. A folding box for the packaging of paper sheets comprising a cardboard box body which is of parallelogram in longitudinal section to provide a bottom wall, a top wall, side walls and inclined parallel front and rear walls, said front wall being integral with and hinged to said bottom wall, foldable corner flaps hinged to opposite ends of said front wall and flatly engaging the exterior of said side walls, interlocking tongue and slot means between said corner flaps and top wall of said box to secure the corner flaps against said side walls, a foldable flap integral with the front end of said top wall and separated therefrom by a transverse fold line, said flap being folded inwardly against the inclined front wall, a pull tab cut from said top wall and connected by weakened tear lines which extend to and outwardly along the transverse fold line, whereby the box body may be opened for the individual dispensing of paper sheets by grasping said pull tab and pulling thereon to sever said flap from the top wall and thereby provide a slot across the front top edge of the body and a communicating finger opening in the top wall thereof.

2. A folding box for the packaging of paper sheets comprising a single blank of cardboard which is cut, scored, and folded to provide a bottom wall, side walls having inclined parallel end edges, a top wall, a front end wall integral with said bottom wall having a score line extending transversely thereacross and inwardly folded thereon upon itself to provide an outer front wall section and an inner front wall section, means for securing the inwardly folded inner front wall section substantially flat against the outer front wall section, foldable end flaps integral with the ends of said outer front wall section and overlapping the front ends of the side walls with the front end wall disposed against the inclined front end edges thereof, inwardly foldable locking tongues integral with said end walls and foldable over said top wall, said top wall having slots therein for respectively receiving said locking tongues which interlock with the walls of said slots, a front end flap integral with the front end of said top wall and separated therefrom by a transverse fold line for folding inwardly against the inner side of the folded front end wall, a pull tab cut from the top wall and connected by weakened tear lines which extend outwardly to and along the last mentioned transverse fold line,

5 an inwardly foldable rear end wall integral with said top wall, and releasable locking means for securing the rear end wall in closed position at an angle substantially conforming to that of the rear ends of said side walls.

3. A folding box for the packaging and subsequent dispensing of paper sheets comprising a box body constructed from a single blank of cardboard which is parallelogram shape in side elevation having a bottom wall, a top wall, opposed side walls, an upwardly outwardly inclined front wall, and a rear wall parallel to said front wall; said front wall being integral with and hingedly connected to said bottom wall along a transverse score line, foldable corner flaps connected to opposite ends of said front wall along hinge scores and flatly engaging the exterior of the respective side walls, releasable fastening means connecting each of said corner flaps with an adjacent wall of the box body other than the front wall thereof, a foldable flap integral with the front end of said top wall and connected thereto along a transverse hinge score, said flap being folded inwardly against the inclined front wall, a pull tab defined by a slit cut from the front mid portion of said top wall, weakened tear lines provided in the top wall which extend forwardly from the edges of the slit to and outwardly along the transverse fold line to the respective ends thereof, whereby the box body may be opened for the individual dispensing of the paper sheets by grasping said pull tab and pulling upwardly and forwardly thereon to sever said flap from the top wall along the weakened tear lines and thereby provide a relatively narrow sheet dispensing slot across the front top edge of the body and a communicating finger opening in the top wall thereof.

4. A folding box for the packaging and subsequent dispensing of paper sheets comprising a box body constructed from a single blank of cardboard which is of parallelogram shape in side elevation having a bottom wall, a top wall, 10 opposed side walls, an upwardly outwardly inclined front wall, and a rear wall parallel to said front wall; said front wall being integral with and hingedly connected to said bottom wall along a transverse score line, a front wall reenforcing flap integral with the top of the front wall and connected thereto along a hinge score, said reenforcing flap being folded inwardly against the rear of the front wall and having its inner end engaging the bottom wall, foldable corner flaps connected to opposite ends of said front wall along hinge scores and flatly engaging the exterior of the respective side walls, releasable fastening means connecting each of said corner flaps with an adjacent wall of the box body other than the front wall thereof, a foldable flap integral with the front end of said top wall and connected thereto along a transverse hinge score, said flap being folded inwardly against the inclined front wall, a pull tab defined by a slit cut from the front mid portion of said top wall, weakened tear lines provided in the top wall which extend forwardly from the edges of the slit to and outwardly along the transverse fold line to the respective ends thereof, whereby the box body may be opened for the individual dispensing of the paper sheets by grasping said pull tab and pulling upwardly and forwardly thereon to sever said flap from the top wall along the weakened tear lines and thereby provide a relatively narrow sheet dis-

pensing slot across the front top edge of the body and a communicating finger opening in the top wall thereof.

5. A folding box for the packaging and subsequent dispensing of paper sheets comprising a box body constructed from a single blank of cardboard which is of parallelogram shape in side elevation having a bottom wall, a top wall, opposed side walls, an upwardly outwardly inclined front wall, and a rear wall parallel to said front wall; said front wall being integral with and hingedly connected to said bottom wall along a transverse score line, foldable corner flaps connected to opposite ends of said front wall along hinge scores and flatly engaging the exterior of the respective side walls, snap fastener elements releasably connecting said corner flaps with the side walls, a foldable flap integral

5 with the front end of said top wall and connected thereto along a transverse hinge score, said flap being folded inwardly against the inclined front wall, a pull tab defined by a slit cut from the front mid portion of said top wall, weakened tear lines provided in the top wall which extend forwardly from the edges of the slit to and outwardly along the transverse fold line to the respective ends thereof, whereby the 10 box body may be opened for the individual dispensing of the paper sheets by grasping said pull tab and pulling upwardly and forwardly thereto to sever said flap from the top wall along the weakened tear lines and thereby provide a 15 relatively narrow sheet dispensing slot across the front top edge of the body and a communicating finger opening in the top wall thereof.

NATHAN FLEISCHER.
